UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNET.

1,325,048.

Specification of Letters Patent. Patented Dec. 16, 1919.

Application filed October 1, 1917, Serial No. 194,142. Renewed May 17, 1919. Serial No. 297,905.

To all whom it may concern:

Be it known that I, ARTHUR SIMON, a citizen of the United States, residing at Milwaukee, in the county of Milwaukee and State of Wisconsin, have invented new and useful Improvements in Electromagnets, of which the following is a specification.

This invention relates to lockout switches.

It is particularly applicable to lockout switches, although it may be useful in other fields.

Electromagnets are designed to remain open when the current in their operating winding or windings is high and to close 15 when the current is below a predetermined value. Such switches are particularly adapted for use in starting systems for electric motors, since they may be made to remain open to keep a resistance in circuit 20 when the motor is subjected to an abnormal current, and to close to remove the resistance when the current decreases to a safe value.

Lockout switches usually comprise a closing magnet tending to actuate the switch 25 arm to close the switch, and a holding magnet tending to prevent closing movement of the switch arm. The two magnets produce varying differences in pull for different current values so that for current values below 30 a certain point the closing magnet will predominate and close the switch, but for current values above that point the holding magnet will predominate and hold the switch open. As the closing magnet 35 predominates below a certain current value there is a possibility of the switch closing at the first rush of current, even though the current eventually is high enough in value to hold the switch open, because the current 40 in rising to its high value passes through the low values at which the switch will close.

Various means have been devised for preventing this undesirable closing of the switch when a current that is relatively high 45 in value is first supplied to the switch, most of which means involve the use of a damping coil associated with the magnetic circuit of the closing magnet to produce a lag in the building up of the closing magnet's 50 strength.

One object of the invention is to provide an improved electromagnet wherein current through a winding thereof is controlled to delay the operation of the electromagnet

upon the application of suddenly rising excess current.

Another object is to provide improved means for preventing closing of the switch when current at a relatively high value is first supplied to the switch.

Another object is to provide a lockout switch in which the current through one of the windings is automatically controlled to prevent closing of the switch when current at a relatively high value is first supplied to the switch.

Other objects will appear as the specification proceeds.

An embodiment of the invention is illustrated in the accompanying drawing, in which—

Figure 1 is a side elevation of a lockout switch constructed in accordance with the invention.

Figs. 2 to 6 inclusive are schematic diagrams illustrating different ways of controlling the current through one of the windings of the switch.

The electromagnet comprises in general a switch arm or armature pivoted intermediate its ends. A closing magnet acts on one end of the switch arm in a direction to close the switch, and a holding magnet acts on the other end of the switch arm in a direction to restrain the switch from closing. The two magnets exert relatively different pulls for different current values so that the closing magnet predominates over the holding magnet for relatively low current values and closes the switch, and the holding magnet predominates over the closing magnet for relatively high current values and holds the switch open. The switch arm is normally biased to open position. In the switch illustrated the necessary predominance of the two magnets is accomplished by providing them with independent magnetic circuits whose relative reluctance varies for different current values.

The reluctance of the magnetic circuit of the closing magnet increases more rapidly than the reluctance of the magnetic circuit of the holding magnet, so that the pull exerted by the holding magnet increases much more rapidly than the pull exerted by the closing magnet. Thus, as the current through the magnets increases above a predetermined value, the pull exerted by the

closing magnet rises comparatively little while, because of its relatively slowly increasing reluctance, the pull exerted by the holding magnet continues to rise rapidly.

- 5 Above the predetermined current value the relative reluctance of the closing magnet has increased to such a degree that the pull of the holding magnet predominates over the pull exerted by the closing magnet and the 10 switch will remain open so long as the current remains above the predetermined value. When the current falls below the value at which the switch is set to remain open, the reluctance of the closing magnet has so decreased that the pull exerted by the holding magnet is overcome by the pull exerted by the closing magnet and the switch closes. During the relatively short period of time in which the current is rapidly rising from 15 below the predetermined value to above that value the switch arm is prevented from moving by automatically controlling the current in either the winding of the closing magnet or the winding of the holding magnet, to 20 produce a lag in the pull of the closing magnet, or to increase the pull of the holding magnet. When a lag is produced in the pull of the closing magnet the holding magnet, of course, holds the switch open 25 while the current is passing through the relatively low values at which the switch would ordinarily close. The same effect is obtained by increasing relatively the pull of the holding magnet. If it be desired to 30 control the current through the winding of the closing magnet so as to produce a lag in the pull of the closing magnet an electrical device is shunted across the closing winding so that at the first rush of current 35 the greater proportion of the total current will be shunted around the closing winding, but after an interval of time the said electrical device becomes less effective and the greater proportion of the current passes 40 through the closing winding. This produces the necessary lag in the building up of the closing magnet's strength. If it be desired to control the current through the winding of the holding magnet the electrical device 45 is shunted around the holding winding to cause, when the circuit of the switch is first closed, a greater proportion of the current to pass through the holding winding. This has the effect of relatively increasing the 50 pull of the holding magnet so that it will predominate over the closing magnet and hold the switch open until the low current values at which the switch is set to close have been passed.
- 55 In Fig. 1, which shows the lockout switch, the switch arm or armature is shown at 1. It carries a movable contact 2, which operates with the stationary contact 3. The closing magnet is shown at 4 and the holding magnet at 5.
- 60 In Fig. 1, which shows the lockout switch, the switch arm or armature is shown at 1. It carries a movable contact 2, which operates with the stationary contact 3. The closing magnet is shown at 4 and the holding magnet at 5.
- 65 In Fig. 1, which shows the lockout switch, the switch arm or armature is shown at 1. It carries a movable contact 2, which operates with the stationary contact 3. The closing magnet is shown at 4 and the holding magnet at 5.

The switch arm 1 is pivoted intermediate its ends to a support 6. The switch arm 1 carries a stop 7 which abuts against the under surface of the support 6 and limits the opening movement of the switch arm.

The upper portion of the switch arm 1 carries the contact arm 8 with which the contact 2 is associated. The contact arm 8 is fulcrumed at 9 on the switch arm 1 and is yieldingly urged toward the switch arm 75 by a coil spring 10. The arrangement is such that the contact 2 is adapted to engage the stationary contact 3 before the switch arm seals with the core of the magnet 4. After the contacts 2 and 3 come into engagement further movement of the switch arm 1 causes the spring 10 to be compressed. The contact 2 is thereby closed against the pressure of the spring 10 and is given sufficient movement after engagement of the 80 contacts to produce a wiping action.

The lower portion of the switch arm 1 carries an adjustable armature 11 which cooperates with the core of the holding magnet 5. The armature 11 is carried by a 90 threaded pin 12 which passes through the switch arm. The armature 11 may be adjusted by turning the same, as will be obvious from the drawing, and may be locked in its adjusted position by the lock nut 13. 95 The adjustment of the armature 11 varies the length of the air gap between the armature and the core of the magnet 5 and therefore varies the effectiveness of the holding magnet.

An electrical device 14, which may be either a condenser, a non-inductive resistance, a resistance having a positive temperature coefficient, a self inductance, a resistance having a negative coefficient, or any 105 other device capable of producing the results hereinafter mentioned, is electrically connected with one of the windings of the switch in the manner hereinafter described. This electrical device may, if desired, be 110 mounted directly on the panel of the switch as shown in the drawing.

Figs. 2 to 6 inclusive show diagrammatically some of the different forms that the electrical device 14 may assume and illustrate the manner of connecting this electrical device across the windings of the switch. In all of these figures the upper coil 4' represents the winding of the closing magnet, and the lower coil 5' represents the winding 120 of the holding magnet.

In Figs. 2, 3, and 4 the electrical device 14 is shunted across the winding of the closing magnet and controls the current in the closing winding so that at the first rush of current a lag is produced in the building up of the flux of the closing magnet. In Figs. 5 and 6 the electrical device 14 is shunted across the winding of the holding magnet so that at the first rush of current the pull 130

of the holding magnet is increased to hold the switch open during rising current.

In Fig. 2 the electrical device 14 is represented as being a condenser shunted across the winding 4' of the closing magnet. When the circuit of the switch is first closed it is obvious that the first rush of current passes through the condenser instead of through the winding 4' of the closing magnet. This causes a lag in the building up of the closing magnet's strength and permits the holding magnet to become effective before the closing magnet attains its full strength.

In Fig. 3 the condenser is replaced by a non-inductive resistance. The first rush of current will pass through the non-inductive resistance on account of the inductance of the winding of the closing magnet. However, shortly after the current is first turned on the greater proportion of the current will pass through the winding 4' of the closing magnet.

In Fig. 4 the electrical device shunted across the winding 4' takes the form of a resistance having a positive temperature coefficient. The ohmic value of this resistance is normally low and at the first rush of current a large percentage of the current is therefore shunted around the winding 4'. However, as the resistance in the shunt circuit becomes heated, its ohmic value increases and then the greater percentage of current passes through the winding 4'.

In Fig. 5 the electrical device 14 takes the form of a self-inductance which is shunted around the winding 5' of the holding magnet. At the first rush of current the self-inductance causes the greater percentage of the current to pass through the winding 5', thus relatively increasing the pull of the holding magnet sufficiently to cause it to hold the switch open until the relatively low current values at which the switch would normally close are passed.

In Fig. 6 the self-inductance of Fig. 5 is replaced by a resistance having a negative temperature coefficient, such for instance as a carbon pile. As the ohmic value of the carbon pile is normally relatively high at the first rush of current the greater percentage of the current will pass through the winding 5'. As the carbon pile becomes heated its ohmic resistance decreases, thus decreasing the proportion of current which passes through the holding winding 5'.

It will now be seen that when current is first supplied to the switch the current in one or the other of the two windings is controlled so as to prevent closing of the switch while the current is passing through the relatively low values and is building up to its full value. Either the current in the closing winding may be controlled to produce a lag in the building up of the closing

magnet's strength while the current is rising, or the current in the holding winding may be controlled to increase the pull of the holding magnet while the current is rising. In either case the switch will be held open at the first rush of current and while the current is passing through its relatively low value to attain its ultimate high value.

Obviously any combination of the devices above described may be used so as to produce both a lag in the pull of the closing magnet and an increase in the pull of the holding magnet. Furthermore, the electrical device 14 may take other forms than those herein disclosed, as the forms herein disclosed are merely exemplary.

The invention has been described in connection with a lockout switch having two coils connected in series. It is obvious that these coils might be connected in any other way. Furthermore, the invention is applicable to switches of other types, for even if the switch has only one winding the electrical device for initially controlling the passage of current through the winding may be shunted around this winding to produce a lag in the pull of the winding to prevent closure of the switch while a current relatively high in value is building up or passing through its low values.

What I claim is:

1. A lockout switch comprising an armature, an electromagnet tending to move the same, means associated with the switch for holding the armature against movement when the current to the switch is above a predetermined value, and means for automatically controlling the current in the winding of said electromagnet for modifying the normal pull of the magnet when current is first supplied to said winding.

2. A lockout switch comprising an armature, an electromagnet tending to move the same, means associated with the switch for holding the armature against movement when the current to the switch is above a predetermined value, and means connected in shunt with the winding of said electromagnet for modifying the normal pull of the magnet when current is first supplied to said winding.

3. A lockout switch comprising an armature, an electromagnet tending to move the same, means associated with the switch for holding the armature against movement when the current to the switch is above a predetermined value, and means for automatically controlling the current in the winding of said electromagnet for modifying the strength of the magnet when the current is first supplied to said winding.

4. A lockout switch comprising an armature, an electromagnet tending to move the same, means associated with the switch for holding the armature against movement

- when the current to the switch is above a predetermined value, and an electrical device connected in shunt with the winding of said electromagnet for controlling the amount of current passing through said winding. 45
5. An electric switch comprising an armature, an electromagnet acting upon the armature and tending to close the switch, an electromagnet acting upon the armature and tending to hold the switch open, and an electrical device connected in shunt with the winding of one of said electromagnets for controlling the current in said winding for the purpose described. 50
6. An electric switch comprising an armature, an electromagnet acting upon the armature and tending to close the switch, an electromagnet acting upon the armature and tending to hold the switch open, and means for automatically controlling the current in the winding of one of said electromagnets when the current is first supplied to the switch for causing the switch to remain open when a relatively high current is passing through its low values. 55
7. An electric switch comprising an armature, an electromagnet acting upon the armature and tending to close the switch, an electromagnet acting upon the armature and tending to hold the switch open, and means comprising an electrical device connected in shunt with the winding of one of said electromagnets to cause the switch to remain open when a relatively high current is passing through its low values. 60
8. A lockout switch comprising an armature, an electromagnet tending to move the same, means associated with the switch for holding the armature against movement when the current to the switch is above a predetermined value, an auxiliary circuit associated with the winding of said electromagnet, and means whereby the current in
- said auxiliary circuit and in said winding is so proportioned when current is first supplied to the winding as to alter the normal pull of the magnet. 65
9. An electric switch comprising an armature, an electromagnet acting upon the same tending to close the switch, an electromagnet acting upon said armature tending to hold the switch open, an auxiliary circuit associated with the winding of one of said electromagnets, and means whereby when current is first supplied to the switch the current is so proportioned in said auxiliary circuit and said winding as to cause the switch to remain open when a relatively high current is passing through its low values. 70
10. An electromagnet comprising an armature, a magnet acting on said armature to move the same, means associated with said armature for holding the same against movement when the current through the electromagnet is above a predetermined value, and means for automatically controlling the current in said magnet for modifying the normal pull thereof when current is first supplied to the electromagnet. 75
11. An electromagnet comprising a pivoted armature normally biased in one position, a winding acting on said armature to move the same to another position, a second winding acting on said armature to retain the same in its normal position, and means associated with one of said windings for modifying the relative effects thereof when suddenly rising current is applied to the electromagnet. 80

In witness whereof, I have hereunto subscribed my name in the presence of two witnesses.

ARTHUR SIMON.

Correction in Letters Patent No. 1,325,048.

It is hereby certified that in Letters Patent No. 1,325,048, granted December 16, 1919, upon the application of Arthur Simon, of Milwaukee, Wisconsin, for an improvement in "Electromagnets," an error appears in the printed specification requiring correction as follows: Page 1, line 8, for the words "lockout switches" read *electromagnets*; and that the said Letters Patent should be read with this correction therein that the same may conform to the record of the case in the Patent Office.

Signed and sealed this 30th day of March, A. D., 1920.

[SEAL.]
